SAFETY SKI FASTENING

Jean Joseph Alfred Beyl, Nevers, France

Application August 10, 1949, Serial No. 109,540

Claims priority, application France
December 4, 1948

4 Claims. (Cl. 280—11.35)

1

Generally, a skier's shoe is fastened to the ski by means of a stirrup rigid with the ski. The shoe moreover is firmly retained within said stirrup by an oblique rope or strap. The consequence is that the skier's leg is subjected to all the torsional stresses transmitted through such a long lever as is constituted by the ski and that accidents, e.g. broken legs, sprained knees, and so on, are frequent.

My invention is concerned with a device intended to avoid the said accidents.

With this end in view, in the fastening according to my invention, a turntable on which the user's foot is rested and which is provided with means to secure the straps or cables that connect the user's foot with said turntable is pivoted to the ski, and resilient means are provided to keep the longitudinal axis of said turntable parallel with that of the ski.

Owing to such an arrangement the foot is no longer connected rigidly with the ski, and in the case of abnormal movements of the ski, the foot-supporting turntable is not compelled to partake of them since the said turntable will rotate with respect to the ski so that no dangerous torsional stresses are transmitted to the skier's foot.

The ways by which said turntable is pivoted to the ski as well as the means to keep it in normal position are numerous. A few embodiments of the fastening designed on the principle just defined will now be described for the purpose of exemplification and by no means for the purpose of limitation, reference being had to appended drawings.

Figure 1 is a vertical section of a first embodiment of the fastening taken on the longitudinal axis of the ski.

Figure 2 is a plan view of the fastening with the turntable removed.

Figures 3 and 4 diagrammatically illustrate modifications of the resilient means.

Figure 5 is a vertical section of a further embodiment.

Figure 6 is a sectional view taken on line VI—VI in Fig. 5.

In the embodiment illustrated in Figs. 1 and 2 a turntable 1 equal in width to the ski and slightly longer than the skier's boot is mounted on the top of the ski 2 for swinging motion about the axis $x-y$. Rigid with said turntable is a conventional stirrup 3 adapted to house the cap of the boot. Said turntable 1 in addition is provided with apertured lugs 4 or similar means through which straps are threaded for the purpose of keeping the boot engaged in the stirrup 3 and

2

consequently to make it rigid with the turntable 1. Contingently, hooks may be provided at that place for the anchorage of the oblique pull cables.

The turntable 1 is secured together with the stirrup 3 by means of screws 5 on top of a disc 6 provided with a central stud comprising two differently shaped sections, viz.: an upper oblong section 7 adjacent to the disc 6 and a bottom cylindrical section 8 housed in a footstep 9 provided in a casing 10 secured in a recess 11 provided in the ski. Said casing 10 is secured to a sole plate 12 which in turn is secured to the ski by means of screws 13. The sole plate 12 is provided with a circular central aperture 14 formed with a rabbet 15 that cooperates with a similar rabbet 16 formed at the periphery of the disc 6. Such a rabbet joint is intended to prevent the disc 6 from being lifted as the ski is canted by its user.

In this manner a playless centering of the disc 6 is ensured by the pivot 8 and the plate 12, the latter moreover being useful to rigidly connect the whole mechanism housed in the casing 10 with the ski.

The oblong section 7 of the central stud is formed with opposite flat portions 17 against which flat metal members 18 are normally pressed by springs 19, e.g. four of them on each side, guided in tubes 20. Grub screws 21 which are easily accessible from the outside of the casing are screwed through holes tapped in plates 22 that close the outer ends of the tubes 20 for the purpose of adjusting the initial stress on the springs 19. Consequently, the turntable 1 can swing about the axis $x-y$ but as soon as the cause of its angular displacement has disappeared it is restored to its original position by the action of the springs 19 upon the flat portions 17.

An arcuate groove 23 is milled in the ski to allow the lugs 4 to partake of the rotation of the turntable 1.

If in sliding downhill or in the negotiation of a curve which is made particularly difficult e.g. on account of a change in the character of the snow the turntable 1 should rotate through a certain angle about the axis $x-y$, it will be returned to its original position by the action of the springs 19 as soon as the action thereon is relieved to some extent. In this manner the turntable is restored to normal position whenever it has been displaced through an angle less than 90° .

In a fall, e.g. when the ski pricks into the snow, the turntable 1 will rotate as much as necessary to keep the strain on the skier's leg below the limit at which it might be damaged. As the

skier gets up again the device is restored automatically to normal position provided the angular displacement did not exceed 90°.

The initial stress on the springs 19 should be such that the turntable 1 and the stirrup 3 rigid therewith can only be rotated by a torsional stress exceeding those involved in safe ski sliding. The springs 19 are the more effective as the flat portions 17 are longer.

Preferably, the plate 12 is flush with the ski.

The tubes or sleeves 20 in which the springs 19 are housed are preferably made of Duralumin in order to exclude icing risks and to make the whole device lighter in weight. In fact, all such metal kinds or grades that are consistent with a satisfactory operation of the device may be used.

The turntable 1 may be made of spring steel, in which case an additional safety is afforded in the case of a simple torsionless forward fall since as a result of a small deflection of the table and a consequent slight lifting of the eyed lug 4 the strain on the skier's joints is lessened.

Instead of the springs 19, one or several pairs of leaf springs 25 may be used which are fixed at their ends and normally pressed against the flat portions 17 as shown in Fig. 3, their positions in the deflected position of the turntable being as shown in broken lines.

Still a further possibility is to pivot the turntable 1 to the disc 6 by means of a wholly cylindrical stud and to anchor either end of the turntable to the top of the ski through a tension spring 26 as shown in Fig. 4. In that case any deflection of the turntable 1 from its normal position will increase the stress on the spring 26 and consequently their effectiveness in returning said turntable. The said springs 26 may be housed in sleeves arranged either on top of the ski or housed in recesses in the top side of the latter.

In the embodiment illustrated in Figs. 5 and 6 a turntable 1 equal in width to the ski 2 and slightly longer than the skier's shoe carries a stirrup 3 into which the user slips the cap of his shoe and an eyed lug 4 through which the foot-retaining strap is threaded. The turntable 1 with the stirrup 3 carried thereby is secured to a disc 6 provided with a central stud formed with an oblong section 7 and a cylindrical section 8. A steel plate 30 resting directly on the ski surrounds a circular rabbet 31 on the pivot 6-7-8 and prevents it from getting out of its housing in the ski.

Boxed in a recess 33 milled in the ski is a one-piece cartridge 32 cast of a light alloy and bored throughout with one single hole in which a pair of hollow pistons 34, 35 are received which are located at either side of the pivot 6-7-8.

Arranged within each of said hollow pistons are a plurality of nested coaxial reversely coiled springs 36, whereby a maximum force is obtained within a piston of minimum diameter. The said springs are rested at their one end on the bottom of the related hollow pistons 34 or 35 and are stressed at their other ends by means of grub screws 37, 38 received in the internally screw-threaded ends of the cartridge 32. Said screws 37, 38 are formed at their free ends with a plain stud 39, 40 received each in the related hollow pistons 34, 35 in such a manner that same is correctly centered. Consequently, the said pistons 34, 35 are pressed by the springs 36 into engagement with the flat sides of the oblong section 7 of the stud and tend to keep said sides at right angles to the longitudinal axis of the

ski. Since the pistons are reliably guided within the ski their action upon the sides of the pivot stud will remain the same for each particular value of the deflection of the turntable 1. Just as in the embodiment according to Figs. 1 and 2 the skier's boot is secured to the ski by resilient means which allow for a certain angular displacement of the boot about an axis at right angles to the top side of the ski consequent to a torsional stress and by which the shoe is restored to normal position as soon as the force that urges it away from said position decreases. By virtue of this arrangement the torque exerted upon the oblong section 7 of the pivot stud by the elastic means remains substantially constant. Effectively, while the springs are stressed more and more as the deflection of the turntable 1 increases, the said stresses are exerted upon the oblong section 7 through shorter and shorter lever arms. In this manner, the resistance to be overcome remains substantially constant, whether at the beginning or towards the end or in the course of the angular displacement.

The cylindrical section of the pivot stud is mounted in a hole 41 bored through the cartridge 32.

It will be appreciated that the invention can be carried into effect in a great many ways and that the embodiments described hereinbefore should be considered only as nonlimitary examples.

What I claim as new is:

1. In combination with a ski, an elongated foot-supporting turntable swingable about an axis at right angles to the top side of said ski, means to secure rigidly the skier's boot to said turntable, a downwardly projecting cam rigid with the lower side of said turntable and coaxial with said axis a rigid member in contact with the cam, and resilient means permanently urging said rigid member against said cam so as to bring the turntable rigid therewith towards a position coaxial with the ski, when said turntable has been turned away from said coaxial position.

2. In combination with a ski, an elongated foot-supporting turntable swingable about an axis at right angles to the top side of said ski, means to attach the skier's boot to said turntable, a downwardly projecting cam rigid with the lower side of said turntable and coaxial with said axis and provided with at least one flat vertical face at right angles to the longitudinal axis of the ski, at least one rigid member with a substantially plane vertical end face in contact with said cam when said turntable is in a position coaxial with said ski means for guiding said member for parallel motion in the longitudinal direction of the ski and, resilient means housed in said ski and urging permanently the rigid member against said cam so as to bring the turntable towards a position coaxial with the ski, when said turntable has been turned away from said coaxial position.

3. In combination with a ski, an elongated foot-supporting turntable swingable about an axis at right angles to the top side of said ski, means to attach the skier's boot to said turntable, a downwardly projecting cam rigid with the lower side of said turntable and coaxial with said axis and provided with two flat vertical faces on diametrically opposite sides of said cam, a pair of rigid members on opposite sides of said cam and each provided with a substantially plane vertical end face adapted to bear with a corresponding flat face of said cam, means for guid-

ing said members for parallel motion in the longitudinal direction of the ski and resilient means housed in and urging permanently said rigid members upon said cam so as to bring the turntable towards a position coaxial with the ski, when the same has been turned away from said coaxial position.

4. In combination with a ski, an elongated foot-supporting turntable swingable about an axis at right angles to the top side of said ski, means to attach the skier's boot to said turntable, an open-ended tubular member embedded in said ski and extending in the longitudinal direction of the ski on both sides of said axis of rotation, at each end of said tubular member a screw engaged in said tubular member, a cam rigid with said turntable and projecting downwardly from the lower side of said turntable into said tubular member and coaxially with said axis of rotation and provided with two flat vertical faces on di-

5

metrically opposite sides of said cam, on each side of said cam a piston guided in said tubular member and provided with a flat end face adapted to bear on a corresponding flat face of said cam, and for each piston at least one spring bearing on one side on said piston and on the other side on the corresponding screw.
